(57) **CLAIM**

The ornamental design for a pair of aircraft wings, as shown and described.

DESCRIPTION

FIG. 1 is a perspective view taken from a top, front, left side pair of aircraft wings according to our design shown on an aircraft shown in dotted lines;

FIG. 2 is a top plan view of the pair of aircraft wings of FIG. 1 with engine nacelles and pylons of the aircraft removed for clarity;

FIG. 3 is a bottom plan view of the pair of aircraft wings of FIG. 1;

FIG. 4 is a front elevation view thereof;

FIG. 5 is a rear elevation view thereof;

FIG. 6 is a left side elevation view thereof; and,

FIG. 7 is a right side elevation view thereof.

Throughout the Figures, where shown: (i) the dotted lines showing environment are for illustrative purposes only and form no part of the claimed design; (ii) the unshaded surfaces do not form part of the claimed design; and (iii) the dash-dot lines illustrate unclaimed boundaries of surfaces claimed as part of the design.
